UNITED STATES PATENT OFFICE.

RUDOLF SALZER, OF TRENTON, NEW JERSEY, ASSIGNEE TO THE DE LAVAL STEAM TURBINE COMPANY.

CENTRIFUGAL PUMP.

No. 896,585.

Specification of Letters Patent. Patented Aug. 18, 1908.

Application filed April 7, 1906. Serial No. 310,457.

To all whom it may concern:

Be it known that I, RUDOLF SALZER, a subject of the Emperor of Austria-Hungary, residing at Trenton, in the county of Mercer and State of New Jersey, have invented a certain new and useful Improvement in Centrifugal Pumps, of which the following is a specification.

The invention relates to multiple centrifugal pumps, and consists in the means for equilibrating liquid pressure exerted at opposite ends of the series of impellers; in the means for preventing entrance of air at the shaft journal on the delivery side of the pump, and to the construction of the pump, all as more particularly pointed out in the claims.

In the accompanying drawing—Figure 1 is a vertical axial section of my centrifugal pump. Fig. 2 is an enlarged section showing in detail the front balancing chamber.

Similar numbers of reference indicate like parts.

1 is the cylindrical pump casing. 2 the front head having the chamber 3, communicating with the suction pipe 4. The rear head 5 has an annular chamber 6 communicating with the delivery passage 7. The casing and heads are horizontally divided in the usual way. On the shaft 8 are the impellers 9, 10, 11 and 12, having the usual vanes 13. Surrounding each impeller is a diffuser formed of an annular plate 14 having lateral vanes 15 which vanes carry a narrow ring 16. In the diffuser of impeller 1 said ring is seated in a recess between the casing 1 and head 2. In the diffusers of the remaining impellers the rings are seated in recesses between the casing and the internal partitions. In the diffusers of impellers 10 and 11 the annular plate 14 is circumferentially flanged, and said flange is received on a shoulder on the periphery of the annular partitions 17. In the diffuser of impeller 12, the plate 14 has a flange which rests on an inner partition wall

18 of the chamber 6 in the rear head 5. Each diffuser has, therefore, one wall formed by the ring plate 14 and the other by a portion of the casing (head or partition as the case may be) with the vanes extending in the usual way from wall to wall. Between the diffuser of each impeller and the inlet of the next impeller in series is a passage formed by the partition 17, and partition 19, said partitions being connected by the guide vanes

20, which may be cast integrally with them. The partition 19 is connected by a circumferential wall 21 to a parallel partition 22, which forms, as already described, one wall of the diffuser associated with each of the impellers 10, 11, 12. The two partitions 19 and 22 with the circumferential wall 21 may be integral and secured to the casing 1, by screw bolts 23. On the outer periphery of wall 21 is a tongue 24, which fits into a groove in the casing.

Between the front head 2 and the first impeller 9 of the series, is formed a chamber 25. Surrounding said chamber is a loose ring 26, seated in a recess in the head 2 and having flanges which alternate with similar flanges on the front side of the impeller 9. Another loose ring 27 forms an inner circumferential boundary of chamber 25 and is seated in said head 2, and provided with flanges which receive between them a flange on said impeller. The chamber 25 thus lies between the rings 26 and 27. Between each of the partitions 19 and the successive impellers are flanged rings 28, similar to ring 27, these rings forming the joint between the impeller and the adjacent partition 19.

Between the last impeller 12 and the rear head 5 is a chamber 29 surrounded by a loose ring 30, which is seated in the head 5 wall 18 and has two flanges which receive between them a flange on the impeller 12. The inner circumferential periphery of chamber 29 is formed by an enlargement 31 of a bushing 32 which extends over a shoulder on the hub of impeller 12 and over a fixed collar 33 on shaft 8, against which collar said hub abuts. The bushing 32 extends through a bearing in the head 5 and is received in a packing gland 34. Outside of the ring 30 and between the impeller 12 and wall 18 is a clearance space 35. The chamber 29 communicates with the front chamber 25 by means of a pipe 36, in which is a valve 37.

The hub of impeller 9 has a sleeve projection 38 which is seated in a recess in the hub of impeller 10, and the hub of impeller 10 is seated in that of impeller 11, and the hub of impeller 11 in that of impeller 12. In this way tight joints between the hubs are formed and the shaft protected from corrosion. The front end of the hub of impeller 9 bears against two half rings 39 which are placed in a groove on shaft 8. Adjacent to

said groove is a fixed collar 40. An enlargement 41 of bushing 42 extends over the collar 40 and half rings 39, and is seated on a shoulder in the hub of impeller 9. Said 5 bushing 42 extends through a bearing in the head 2 and is received in a packing gland 43. In the upper part of the casing are openings 44, which serve to admit priming liquid to the several impellers. Several openings 45 10 serve to drain liquid from the apparatus when it is at rest. All of these openings may be internally threaded as shown to receive screw closing plugs.

The object of the chambers 25, 29 and 15 connecting pipe 36 is to balance the liquid pressure on the faces of the impellers 9 and 12 at the ends of the series. The pressure areas on the said impeller faces may be directly proportioned with respect to the relative pressures exerted on them, or, preferably, approximately proportioned and an adjustment of relative pressures effected by means of the valve 37. The pressure exerted on opposite faces of the end impellers 20 tends to force the hubs together, thus preventing leakage at the joints. Some leakage from chamber 25 into the chamber 3 and from chamber 29 into the adjacent stuffing box is of course unavoidable; but the liquid 25 so escaping from chamber 25 is replaced by liquid from chamber 29 received through the pipe or transfer duct 36 whereby the pressure in chamber 29 is maintained at a lower pressure than in the clearance space 35 and 30 at the same pressure or nearly the same pressure (depending upon the adjustment of the valve 37) as the pressure in chamber 25; and from this more or less complete 35 equalization of pressure in these two chambers, the balancing action, which is the purpose of transfer duct 36, results. As the chamber 29 contains liquid under a pressure above that of the atmosphere the entrance of air to the pump around the shaft 40 45 journal at the delivery end is thus prevented. Such leakage as passes from said chamber to the shaft journal assists in lubrication.

In another application for Letters Patent Serial No. 310,456, filed simultaneously 50 herewith, I have described and claimed the construction of an annular chamber embodying two loose concentric rings seated between the front side of the impeller and the casing wall, and also the construction of the 55 diffuser formed by a substantially flat ring provided with vanes and a second ring and seated in the annular passage beyond the impeller outlet as herein described. I have also described and claimed in said application, the construction of the shaft journals 60 substantially as herein shown and described. Said constructions are therefore not herein claimed.

I claim:

65 1. The combination in a multiple centrifugal pump, of a series of impellers and a casing therefor having two liquid receiving chambers, whereof the outer faces of the end impellers of the series form walls with a duct connecting said chambers, and a valve in said duct.

2. The combination in a multiple centrifugal pump, of a series of impellers and a casing therefor having (1) an annular chamber formed between the front side of the first impeller of the series and a casing wall and surrounding the inlet of said impeller, and (2) an annular chamber between the rear side of the last impeller of the series and a casing wall, with a duct connecting said annular chambers, and a valve in said duct. 70

2. The combination in a multiple centrifugal pump, of a series of impellers and a casing therefor having (1) an annular chamber formed between the front side of the first impeller of the series and a casing wall and surrounding the inlet of said impeller, and (2) an annular chamber between the rear side of the last impeller of the series and a casing wall, with a duct connecting said annular chambers, and a valve in said duct. 75

3. The combination in a multiple centrifugal pump, of a series of impellers and a casing therefor having (1) an annular chamber formed between the front side of the first impeller of the series and a casing wall and surrounding the inlet of said impeller and (2) an annular chamber between the rear side of the last impeller and a casing wall, a floating ring circumferentially bounding said last named 80 chamber and forming a loose joint with said last impeller and said casing wall, a duct connecting said annular chambers and a valve in said duct. 85

4. The combination in a multiple centrifugal pump, of a series of impellers, a shaft therefor, a casing having bearings for said shaft and (1) an annular chamber formed between the front side of the first impeller of the series and a casing wall and surrounding the inlet of said impeller and (2) an annular chamber between the rear side of the last impeller and a casing wall, a ring circumferentially bounding said last named chamber and forming a loose joint with said last impeller and said casing wall, a bushing seated on the hub of said last impeller and interposed between said shaft and its bearing in said casing and forming the inner circumferential boundary of said chamber, a duct connecting said 90 annular chambers and a valve in said duct. 95

5. In a multiple centrifugal pump, a series of impellers, and a casing therefor having an annular chamber and a surrounding clearance space both formed between the rear side of the last impeller of the series and a casing head, a loose ring forming a joint between said clearance space and said chamber, and means for equalizing the liquid pressure in said chamber and the liquid pressure exerted 100 on the outer face of the first impeller of said series. 115

6. The combination in a multiple centrifugal pump of a series of impellers, a casing, and a shaft for said impellers journaled therein; the said casing having an annular chamber surrounding the shaft and formed between a casing wall and the rear face of the last impeller of the series, and the said chamber having loose joints in its inner and outer 120 125 130

circumferential walls whereby leakage from the pump delivery is permitted to pass through said chamber to the shaft journal.

7. The combination in a multiple centrifugal pump of a shaft, a fixed collar thereon, a series of impellers on said shaft, the hub of the last impeller of the series abutting against said collar and the hub of each remaining impeller having a sleeve projection seated in 10 a recess in the next adjacent impeller hub, two removable half-rings seated in a groove in said shaft in front of the hub of the first impeller of the series and a holding ring surrounding said half-rings.

15 8. A centrifugal pump comprising in combination a series of rotary impellers, and a casing inclosing said impellers, having diffuser passages for the several impellers receiving their discharge, said casing having 20 passages connecting each diffuser passage except the last to the intake of the next impeller, and having chambers in which the impellers revolve, said chambers each in fluid connection with the space between the 25 periphery of the corresponding impeller and the mouth of the corresponding diffuser passage, and adapted to receive and be filled by fluid from such space, said casing having also a balancing chamber, between the last impeller and the head of the casing, which is 30 in restricted communication only with the chamber in which said last impeller revolves, and a transfer duct connecting said balancing

chamber with the space between the front side of the first impeller and the casing, there 35 being restricted waste from such spaces.

9. A centrifugal pump comprising in combination a series of rotary impellers, and a casing inclosing said impellers, having diffuser passages for the several impellers receiving their discharge, said casing having 40 passages connecting each diffuser passage except the last to the intake of the next impeller, and having chambers in which the impellers revolve, said chambers each in 45 fluid connection with the space between the periphery of the corresponding impeller and the mouth of the corresponding diffuser passage, and adapted to receive and be filled by fluid from such space, said casing having also 50 a balancing chamber, between the last impeller and the head of the casing, which is in restricted communication only with the chamber in which said last impeller revolves, and a transfer duct connecting said balancing 55 chamber with the space between the front side of the first impeller and the casing, there being restricted waste from such space, said transfer duct provided with regulating means.

In testimony whereof I have affixed my 60 signature in presence of two witnesses.

RUDOLF SALZER.
